FIG. 4.

UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

IRONING-MACHINE.

1,327,613.

Specification of Letters Patent. Patented Jan. 13, 1920.

Original application filed October 15, 1914, Serial No. 866,773. Divided and this application filed October 4, 1915. Serial No. 53,904.

To all whom it may concern:

Be it known that I, ALVA J. FISHER, a citizen of the United States, residing at Evanston, Cook county, Illinois, have invented certain new and useful Improvements in Ironing-Machines, of which the following is a specification, this application being divisional of an application filed by me on October 15, 1914, Serial No. 866,773.

10 My invention relates to ironing machines of that type in which a heated shoe coöperates with a padded roll in the ironing operation. One of the principal objects of my invention is to provide a novel and efficient 15 construction of such shoe whereby the ironing surface thereof shall be properly and uniformly heated. My invention involves other and advantageous features of construction which will be apparent from the 20 description hereinafter given.

In the drawings Figure 1 is a side elevation of my machine; Fig. 2 an elevation of one end thereof; Fig. 3 a vertical cross section of the shoe and Fig. 4 a detail section 25 of a portion of the operating mechanism for the shoe.

The same figures of reference are used as in the original application in so far as the same are applicable.

30 Referring to the embodiment of my invention as herein shown, the machine is provided with a supporting frame composed of end frames 1 and the tie-rods 2 connected therewith. Upon the tops of these end frames are supported the bearing brackets 3 for the horizontal driving shaft 4 of the padded roll 5. In so far as my present invention is concerned the driving mechanism for rotating the shaft may be of any desired 35 character. In the present instance the prime mover is an electric motor 6 supported by one of the end frames and adapted to communicate its power from the pulley 7 and belt 8 through suitable driving connections 40 (not shown) to said shaft 4.

Referring to the shoe, the same comprises an arc-shaped hollow body 24 extending longitudinally of the roll and having its ironing surfaces corresponding substantially 45 to the arc or curvature of the roll. At predetermined distances apart there are formed in the interior of the shoe a series of vertical ribs or flanges 25 projecting outwardly, that is away from the roll, and having the func-

tions hereinafter explained. These vertical 55 ribs are formed on the outer side of the curved wall of the shoe which is in juxtaposition to the roll. The shoe also comprises a curved casing 26 preferably of sheet metal and secured along its lower edge to the outwardly extending flange or lift 27 of the body of the shoe and along its upper edge to the outwardly extending flange 28 into which the top edges of the flanges 25 merge. The casing 26 is provided with air inlet 60 openings 26^a and the flange 28 with outlet openings 28^a.

In the present instance, the burner is a gas burner including the gas pipe 29 having a series of slits 29^a, thereby forming a burner. 70 This burner is arranged at the lower point of the arc or crescent-shaped space formed by the body of the shoe and the casing 26, as seen in Fig. 3, in which position it is close to the lower portion of such body and directly below the vertical ribs or flanges 25. 75

One of the main objects of this invention is to provide for the proper and uniform heating of the shoe, that is, the ironing surface thereof and this construction accomplishes this purpose. The flame is at all times directed toward and upon the body 24 and upon the flanges 25, and to insure this action the outlet holes 28^a are located as shown, that is, at extreme upper point of 80 such crescent. Moreover, by the provision of the flanges 25 the heat is conducted thereby inwardly to the shoe body and also distributed more uniformly over the surface of such body than would be possible if such 85 flanges were omitted. 90

As shown in Fig. 3 and by preference, the ironing surface is not the metal surface of the body 24, which is usually made of steel and therefore corrodible, but is made 95 of a sheet of non-corrodible material 30, such as German silver or the like. This sheet is secured along its longitudinal edge at 31 to the lower corner of the shoe body while its upper portion is reversely bent 100 over the top projecting edge of the shoe body and secured thereto in suitable manner at 32. The parts 32 also hold a strip 30' (which might be integral with sheet 30) that extends along the body and is turned 105 upwardly to act as a deflector coöperating with the outlet holes 28^a, with the result that the heated air and the products of com-

bustion are deflected away from the operator.

The shoe body is provided at its opposite ends with depending arms 33 whereby 5 the shoe is supported and capable of a swinging movement toward and away from the roll. The lower ends of the arms 33 are pivoted upon the studs 33^a on the inner sides of the bearing brackets 3, Figs. 1 and 10 4. A rod or rock shaft 34 extends longitudinally of the machine between these brackets and is provided with a handle 35 connected therewith for the purpose of rocking the shaft by hand. Operating connections 15 are provided at opposite ends of the rock shaft and the arms 33 and as these connections are similar a description of one of them will apply to both. One of the connections is shown in detail in Fig. 4. An 20 upwardly extending arm 36 is secured to the rock shaft 34 and pivotally connected by means of the pin or stud 37 thereon to a block 38 having a rearwardly extending rod 39 whose inner end passes through a block 25 40 pivotally connected by means of the stud 41 to one of the arms 33 of the shoe.

When the handle 35 is thrown up in the position shown in Fig. 2, the shoe is in ironing position and the proper tension is afforded by the springs 42 interposed between the blocks 38 and 40. Means for stopping the handle 35 and its oscillating parts in both extreme positions, are provided at each 30 end of the machine comprising collars 43 secured to shaft 34 by set screws 44 and having on substantially opposite sides lateral arms 45 and 46. Arms 45 each have a set screw 47 which is adapted to contact the top face of bracket 3 when the handle 35 is thrown up, and the arms 46 each have a set screw 48 which is adapted to contact the bottom face of bracket 3 when the handle 40 is down. By adjusting the set screws the throw of the handle may be regulated.

45 I claim:

1. In an ironing machine, the combination, with a roll, of a hollow shoe having a body corresponding substantially with the curvature of the roll, and having outlets at 50 its upper portion, means for heating the shoe, and a sheet of non-corrodible material affixed to said body to form the ironing surface thereof, one end of the sheet being ar-

ranged above said outlets to act as a deflector.

55

2. In an ironing machine, the combination of a roll, a hollow heated shoe coöperating therewith having a contact face arranged to span a rear arc of the roll and pivoted at its lower portion in front of its center of gravity to tend easily to fall away from the roll, an operating handle pivoted in rear of said roll, a horizontal rock shaft operated by said handle, an upwardly extending crank arm on said rock shaft, a horizontally extending rod pivotally connected at opposite ends, respectively, to said crank arm and to a point on the shoe intermediate the pivotal axis of said shoe and its contact area, one of said pivotal connections for said rod involving a bearing wherein the rod may slide axially, and spring means for resisting such sliding action of said rod.

70

3. In an ironing machine, the combination of a roll, a hollow heated shoe coöperating therewith pivoted at its lower portion, a handle and yielding connections between the handle and shoe for holding the latter in operating position with a yielding pressure, comprising a rock shaft to which the handle is connected, a crank arm thereon, and a spring pressed rod pivotally connected with the crank arm and the shoe, and also adjustable means for limiting both extreme movements of the handle and its said connections.

75

4. In an ironing machine, the combination of a roll, a hollow heated shoe in rear of said roll coöperating therewith and pivoted at its lower portion, an operating handle pivoted in rear of said shoe, yielding connections between said handle and said shoe for holding the latter in operative position with a yielding pressure comprising a rock shaft to which the handle is connected, a crank arm and a spring-pressed rod pivotally connected with the crank arm and the shoe, and adjustable stop screws for limiting movements of said handle and its connections in both directions.
